MECHANICAL TAKE-UP FOR TEAR STRIP APPLICATOR

Paul W. Jacobsen, Kiel, Wis., assignor to H. G. Weber & Company, Inc., Kiel, Wis., a corporation of Wisconsin

Application May 12, 1954, Serial No. 429,348

3 Claims. (Cl. 271—2.2)

This invention relates to a mechanical take-up for tape applying mechanisms and particularly to a mechanical take-up for a rocker type lay down device employed in a tear strip applicator machine.

It is an object of the present invention to provide novel means for accommodating application of tape to rapidly moving articles.

It is a further object of the present invention to provide novel means for effectively reducing the inertia of a tape supply in a machine for applying a tape to moving articles.

It is another object of the present invention to provide a novel take-up mechanism for use with a rocker type lay down device in applying a tear strip to carton blanks.

Other objects, features, and advantages of the present invention will be apparent from the following detailed description taken in connection with the accompanying sheets of drawings, in which:

Figure 1 is a diagrammatic illustration of a tape applying mechanism for a tear strip applicator machine embodying the take-up device of the present invention and illustrating the initial condition of the apparatus;

Figure 2 is a diagrammatic view similar to Fig. 1 but illustrating the condition of the take-up mechanism just after travel of a carton blank through the apparatus;

Figure 3 is a diagrammatic view similar to Fig. 1 and illustrating the condition of the apparatus just prior to arrival of a second carton blank at the tape applying mechanism;

Figure 4 is a fragmentary side elevational view of the take-up mechanism of the present invention;

Figure 5 is a fragmentary end elevational view of the structure of Fig. 4;

Figure 6 is a fragmentary vertical sectional view illustrating the take-up carriage in front elevation; and

Figure 7 is a fragmentary transverse sectional view illustrating the take-up carriage in side elevation.

As shown on the drawings:

The present invention is particularly adapted for use with a tear strip applicator machine for applying an adhesive tape to moving articles, and particularly to the application of a continuous strip of normally tacky, pressure-sensitive adhesive tape having great tensile strength to a carton blank stamped from a piece of boxboard. In one form of tear strip applicator for carton blanks, the tape is applied along one broad surface of the carton blank, around the leading end surface and thence along a second broad surface on the opposite side of the blank, the tape serving as a "tear strip" after the blank has been formed into a carton for use in opening the carton.

Referring to Figs. 1, 2 and 3, there is illustrated a pair of feed rollers 10 and 11 for delivering a carton blank 12 to a tape applying section 13 of a tear strip applicator machine. An elongated frame 15 is disposed along the path of advancement of the carton blank 12, with its near end 15' extending toward the point from which the blank 12 is advanced, and its far end 15" extending toward the point toward which the article is advanced. The frame

2

15 is mounted at a point between its ends for pivotal movement about an axis 16 that is parallel to a tape applying platen 18 and at right angles to the path of advancement of the blank 12.

5 An applying roller 19 is mounted at the near end 15' of the frame for rotation about an axis 21 that is parallel with the pivotal axis 16. An idler roller 22 is mounted at the near end 15' of the frame between the applying roller 19 and the point from which the blank 12 is advanced, for rotation about an axis 24 that is parallel with the pivot axis 16. Two pilot rollers 26, one on either side of the frame 15, are mounted at the far end 15" of the frame for rotation about an axis 27 that is parallel with the pivot axis 16.

15 Yieldable bias means in the form of a spring 30 that is attached to the near end 15' of the frame, impels the near end upwardly about the pivot axis 16, thereby causing the far end 15" of the frame 15 normally to bear downwardly towards the platen 18 to bring the peripheries of the pilot rollers 26 in closer spaced relation to the platen than is the periphery of the applying roller 19. The frame 15 is then at rest, in normal position (Figs. 1-3). The distance between the periphery of the applying roller 19 and the platen 18 is greater than the height of the blank 12.

The respective spaced relations of the applying roller 19, the pilot rollers 26 and the pivotal axis 16 of the frame 15, in respect to the platen 18, are such that the advancing blank 12 will hold the pilot rollers 26 upwardly away from the platen a distance sufficient to cause the applying roller 19 to bear downwardly (against the force of the spring bias 30) upon the top surface of the blank 12 and thereby press and apply tape 32 to the top surface. The frame is then in tape applying position (not shown).

35 The idler roller 22 is positioned in the frame so that its periphery will not contact the top surface of the blank when the frame is in the applying position with the applying roller 19 bearing upon the top surface of the blank.

After the blank 12 travels past the lay down device including the frame 15, pilot rollers 26 and applying roller 19, the blank travels past a buffering pad and cutter assembly 35 mounted for vertical reciprocation and impelled downwardly and upwardly, as by means of a spring means and a solenoid (not shown), or by means of a mechanically actuated system such as disclosed in my copending application entitled "Mechanical Cut-Off for Tear Strip Applicator," Serial No. 429,350, filed of even date herewith. The assembly 35 comprises a buffering pad 38 and a knife 39.

50 The portion of the working surface of the platen 18 adjacent the tape (beneath the tape in the illustrated machine) is slightly depressed in respect to the general level of the working surface along which the carton blank slides. The depressed portion formed by the platen 18 extends in alignment with the tape 32, and is wider than the tape but narrower than the length of the applying roller 19. The depth of the channel is somewhat greater than the thickness of the tape, and it extends to the right and left (Figure 1) beyond the buffering pad 38 and the applying roller 19, respectively. The buffering pad is narrower than the channel so that it may fit into the channel or depressed portion and press the tape against the depressed portion of the platen surface.

55 In operation of the lay down mechanism, the tape is unwound from a supply roll 40 and is led from the supply to and around the idler roller 22 with its adhesive side out. From thence it is led to the right, adhesive side down, beneath the applying roller 19 and thence along the platen 18 beneath the raised buffering pad 38 until the leading end is directly beneath the knife 39. The leading portion 32' of the tape that extends from

the left end of the buffing pad 38 to the knife 39 is then manually pressed down upon the depressed portion of the surface of the platen 18 to adhere it thereto. It may subsequently be peeled off without soiling the platen or harming the tape. The leading portion has thus been temporarily applied to the platen. The unapplied portion of the tape extends upwardly from the platen to and around the applying roller 19, and thence through the take-up device to be hereinafter described to the supply roll 40.

As the first carton blank 12 is fed from the left by the feed rollers 10 and 11, it is advanced along the platen in the direction of the arrow 41 until the leading end of the blank strikes the pilot rollers 26, whereby the pilot rollers 26 are raised and with them the far end 15" of the applying roller frame 15, thus turning the frame counterclockwise about the pivotal axis 16 against the pull of the spring 30, and thereby causing the applying roller 19 at the near end 15' of the arm to move downwardly into contact with the top surface of the blank 12 with a portion of the tape 32 between the roller 19 and the top surface of the blank.

The tape is thus applied, at this point in the progress of the blank 12 through the machine, to the leading edge surface of the blank and thence along the top surface of the blank to the applying roller point of contact. Since the application of this length of tape on the leading edge and top surfaces is accomplished by the time the blank commences to pull or withdraw fresh tape from the take-up mechanism indicated generally at 44, the strain on the blank which is caused by the sudden commencement of the tape withdrawal is distributed over a portion of the blank that is relatively great in comparison to the portion that would thus be strained were the pull-off to commence when the tape is applied only to the leading edge surface of the blank. The applying roller 19 is located at a point removed from the leading portion of the tape and is normally in spaced relation to the platen 18 and it does not descend until a portion of the blank has passed under it, so that its first contact with the blank is made at a point removed from the leading end edge of the blank.

Continued advancement of the blank peels off the portion of the tape that was initially applied to the platen 18 and turns the tape back on itself so that it becomes applied to the bottom of the blank until all the portion 32' has been transferred from the platen to the bottom of the blank.

After the trailing end of the blank has passed the pilot rollers, the spring 30 returns the applying roller frame 15 to its normal position with the applying roller 19 above the level of the top surface of the blank (Fig. 2).

After the trailing end of the blank has passed the knife 39, the assembly 35 automatically moves down into operative position, whereby the knife 39 severs the tape and the buffing pad 38 presses downwardly upon the platen 18. The length of tape that was drawn out along the platen beneath the pad 38 by the movement of the carton blank prior to the above described severance, is thus pressed by the downwardly moving pad to become the leading portion such as 32' of the next succeeding length temporarily applied to the platen.

In accordance with the presently claimed invention, there is interposed between the tape lay down mechanism above described and the supply roll 40, a mechanical take-up device indicated generally at 44 for reducing the inertia of the tape supply and accommodating rapid supply of tape to the lay down device as required. It will be observed that the take-up mechanism 44 including a spool 50 serves to define a circuitous path for the tape 32 between the supply roll 40 and the lay down device. When the lay down device makes a sudden demand for tape, the take-up mechanism functions to shorten this circuitous path, in the illustrated embodiment by down-

ward movement of the spool 50, to provide the initial supply of tape. The roller 50 is carried by a carriage 51 of relatively low inertia in comparison with the supply roll 40, and the carriage is guided by means of a guide structure indicated generally at 52. Additional guiding rollers 53, 54, 55 and 56 are provided for defining the path of the tape. Means including a cable 60 connected to the carriage 51 is provided for urging the carriage in a direction to extend the path of travel of the tape to take-up slack in the tape as the sudden demand during initial application of the tape to the carton blank subsides.

Thus, as the box blank enters the rocker type applying mechanism heretofore described including the frame 15 and the components carried thereby, the tape applying mechanism or lay down mechanism applies the tape several inches away from the leading edge of the box blank, freely snapping the loose tape tab provided by the tape portion 32' over this leading edge, so that the tape tension and the action of the spool 50 is absorbed in shear only of the bond between the tape and the carton blank.

Spool 50 is mounted on a shaft 62 and is rotatable on the shaft, the shaft being mounted on the lightweight carriage 51 which may be made of aluminum. Carriage 51 is free to travel vertically in a range of approximately six feet within the guide structure 52. The carriage, with its component parts, is extremely light in weight to provide low starting inertia when a carton blank calls for immediate tape pay-off. Bearings assist in the free wheeling of the carriage to provide anti-friction traveling throughout the six foot length of take-up stroke, the bearings also stabilizing the carriage laterally and endwise. In its uppermost position, the restoring means including the cable 60 exert approximately a one pound tension. When a carton blank such as 12 travels through the tape applying station, the spool 50 travels down the guide structure 52 from four to six feet, depending on the speed of the carton blank and other variables, before the tape supply roll 40 gets up to the speed of the blank. Due to the rapid acceleration of the supply roll 40, it not only arrives at box blank speed, but exceeds the speed of the box blank to pay off more tape than that which is actually being applied on the box blank at a particular instant.

The slack in the tape 32 allows the take-up spool 50 to rise and resume nearly its original position at the top of the track as indicated in Fig. 3.

Because the supply roll 40 continues in motion after the first box blank 12 has passed through the station, succeeding box blanks such as 67 in Fig. 3 do not impose as great a tension on the tape as the first blank. As a consequence the travel of the tape take-up spool 50 is considerably less, the spool hunting in about a two foot space near the top of the guide structure 52. With the tape spool 50 in this "hunting" condition, there is not a great differential in tape tension and a relatively uniform and continuous tape pay-off from supply roll 40 is possible. The mandrel of the supply roll 40 is equipped with a friction drum indicated diagrammatically at 68 and a simple friction brake indicated at 69 to apply the slight amount of friction necessary to inhibit over-run of supply roll 40 and thus to prevent excessive tape pay-off when take-up spool 50 is in its uppermost location. The friction brake 69 thus eliminates looping of the tape.

In detail, the illustrated take-up device comprises an upright tube 80 (Figure 4) having a plurality of spacer brackets 81 mounting a guide track 82 for the carriage 51. The tube 80 may be carried by means of a bracket 84 which may be secured with the tape applying structure, which structure in turn may be laterally movable relative to the path of travel of the carton blanks through the machine. For returning the carriage toward its upper position to take-up slack in the tape 32, the tube 80 has a spring 86 secured therein which is connected to cable 60 trained around a pulley 88 carried by the pipe, the cable being attached to the carriage 51 by means of a

clamp down plate indicated at 90 (Figure 6). A bracket 93 mounts the pulley 88 and is slotted or apertured to accommodate the portions of the cable on either side of the pulley which extend downwardly through the bracket.

The guiding structure for the carriage comprises a pair of angle track bars 95 secured to a track bar 96 carried by brackets 81. The angle bars have inturned flanges 95a providing the outer bearing surfaces for the rollers of the carriage and sides 95b providing the side bearing surfaces for the rollers. The track bar 96 provides an inner surface upon which the rollers bear.

As seen in Figs. 6 and 7, a shaft 97 at the upper end of the carriage 51 carries rollers 98, a lower shaft 100 carries rollers 101, while lateral rollers 102 are carried by spaced ears 103 projecting laterally from the body of the carriage 51.

The leader spool 50 has a generally hour glass shape with a central reduced diameter tape receiving portion and diverging frusto conical side portions such as 50a and is carried on the shaft 62 secured centrally of the carriage 51.

The carriage 51 is thereby constrained both laterally and endwise for relatively frictionless traveling throughout the six foot length of the take-up stroke. The tension of spring 86 is adjusted by means of a fastening bolt 110 which can be located in any one of a plurality of vertically spaced holes 111 in the tube 80 adjacent the lower end thereof.

It will be apparent that modifications and variations may be effected over a wide range without departing from the scope of the novel concepts of the present invention.

I claim as my invention:

1. In combination, a tape supply, a tape applying device for applying tape received from said tape supply to a traveling article, a take-up device operably receiving said tape and interposed between said supply and said applying device to establish a circuitous path for tape from said supply to said applying device, said take-up device being movable to shorten said circuitous path and thereby to provide a supply of tape to said applying device independent of delivery of tape from said tape supply, and said take-up device having an effective inertia less than the inertia of said supply, said take-up device thereby being operative to absorb an initial high demand for tape by said applying device prior to delivery of tape by said tape supply at the speed of travel of the article, the take-up device having means providing progressively increasing resistance to movement thereof in a direction to shorten said circuitous path to progressively increase the force exerted by the tape tending to pull tape from the supply thereof to rapidly bring the speed of the tape

delivered from the supply up to article speed, said take-up device comprising a carriage, a guideway for said carriage, and a tape receiving means carried by the carriage, said carriage being movable along said guideway to shorten the path of the tape from said supply to the applying device.

2. A tape applying mechanism comprising a rocker type tape lay down device for applying tape to a succession of articles traveling at substantially constant speed, a tape supply roll for supplying tape to said lay down mechanism, a take-up assembly having a spool means for receiving said tape and defining a circuitous path for tape from said supply roll to said lay down mechanism, an upright support structure including a guideway for guiding said spool means for movement to reduce the length of the path of said tape from said supply roll to said lay down device, and means urging said spool means in a direction to extend the path of said tape from said supply roll to said lay down device, said spool means being movable along said guideway to define a shorter path for said tape from said supply roll to said lay down device to supply tape to said lay down device during a period when the tape is applied to an article moving faster than the speed at which tape is supplied from the supply roll.

3. In combination, a tape supply roll, a rocker type tape applying mechanism for receiving tape from said roll and applying the same to articles traveling through said lay down device, and a take-up assembly between said tape supply roll and said lay down device and having a tape receiving means for defining a circuitous path for tape from said supply roll to said lay down device, a guiding structure defining a path of travel to reduce the length of said circuitous path for tape from said roll to said lay down device, a carriage having rollers cooperating with said guiding structure for movement along said path and carrying said tape receiving means, an upright tube carrying said guiding structure and having a pulley at the upper end thereof, a flexible cable connected with said carriage and extending around said pulley and into said upright tube, and a spring secured within said tube and connected at one end with said cable for urging said carriage to its upper position with the tape receiving means defining an elongated circuitous path for the tape.
